[57] ABSTRACT

An electrically powered can opener has the features of power-pierce and automatic shut-off. A removable cutter mounting plate is separably mounted with respect to the can piercing hand lever to effectively utilize the above features. The cutter mounting plate is operatively connected to the frame with a spring biased latch member engaging cutter mounting plate and is removably located within an aperture in the hand lever. This second pin member-hand lever connection, in conjunction with the mounting means for the hand lever on can opener frame, enables the hand lever to effect the pivoting of the cutter element on the cutter mounting plate toward and away from the can feed wheel, and the appropriate orientation of a movable can guide with respect to the can feed wheel.

**CAN OPENER WITH POWER PIERCE,
AUTOMATIC SHUT-OFF, AND REMOVABLE
CUTTER MOUNTING PLATE**

**BACKGROUND AND BRIEF DESCRIPTION OF
THE INVENTION**

This invention relates to an improvement on the can opener disclosed in the pending U. S. Pat. application Ser. No. 177,688 filed Sept. 3, 1971, now U.S. Pat. No. 3,724,069 and entitled "ELECTRIC CAN OPENER WITH REMOVABLE CUTTER MOUNTING PLATE AND PIVOTALLY ATTACHED HAND LEVER" and owned by the same assignee.

The present invention relates to a power operated can opener having the features of power-pierce, automatic shut-off, and a removable cutter mounting plate which carries the cutting element thereon. The cutter mounting plate and the can piercing hand lever are separable elements but interconnected by a second pin member which extends from the cutter mounting plate and is removably and pivotally located within an aperture in the can piercing hand lever. A first cutter mounting plate pin member extends through suitable bearing opening in the can opener upright frame and is engaged by a spring biased latch member to operably retain, yet at the same time permit the removability of, the cutter mounting plate (which carries the cutting element thereon) for cleaning or other purposes.

The cutter mounting plate is suitably contoured and apertured to uniquely locate both a fixed can guide and a movable can guide on the frame structure and to permit the can piercing hand lever to effect the pivotal movement of both the cutter mounting plate and the associated movable can guide which extends through an opening in the cutter mounting plate. The interconnection of can piercing hand lever with the can opener frame is such that both the pivotal movement of same is permitted as well as a substantially horizontal movement within an elongated opening in the frame. Also, the pivotal pin member, which extends from the hand lever through the above mentioned elongated frame opening, participates in effecting the power-pierce and automatic shut-off, as well as the swinging of the cutter mounting plate to permit normal can opener operation.

An object of the invention is to provide an electrically powered can opener with power-pierce, automatic shut-off, and a uniquely constructed removable cutter mounting plate.

Another object of the invention is to provide an electric can opener of the character described above which is capable of being produced more economically and which requires substantially less torque or force to swing a can piercing hand lever upwardly for the normal can opening operations.

A further object of the invention is to provide an electrically operated can opener of the character described above that substantially reduces any tendency to tilt or to rotate the entire can opener on the surface which it rests. Such tilting normally occurs as the user would swing the can piercing hand lever upwardly during the initial operation of the can opener or to release an opened can from the can opener.

Another object of the invention is to provide a power-operated can opener which mounts the cutting element on a cutter mounting plate and which permits the easy removability of the cutter mounting plate from the

can opener. It is a feature of this object that the cutter mounting plate is separable from the can piercing hand lever.

A further object of the invention is to provide an electrically operated can opener which has a cutter mounting plate carrying the cutting element thereon and in which the cutter mounting plate is easily removable, while at the same time permitting the can piercing hand lever to remain permanently assembled to the frame of the can opener.

A further object of the invention is to provide an electric can opener which has a removable cutter mounting plate carrying the cutting element thereon, same being simple and easy to remove or re-install with respect to the can opener frame. It is a feature of the invention that the can opener operates to automatically align certain pivotal structural features of the can opener (such as the can piercing hand lever) when it is necessary to re-install the combined parts of the remainder of the can opener.

Still further object of the invention is to provide a can opener of the character described which has a uniquely constructed movable can guide cooperating with a fixed can guide during the cutting operation and which automatically moves the movable can guide to the required out of the way position through engagement with the cutter mounting plate whenever the can piercing hand lever is swung to its upwardmost position. At all other times, the cutter mounting plate is free of the movable can guide during the other phases of operation of the opening of a can.

Another object of the invention is to provide an electric can opener of the character described which locates the fixed can guide with respect to the remainder of the can opener in such a manner that the rim or flange of the can stays on the can feed wheel. It is a feature of this object that the uniform tilting of an engaged can during all phases of the operation of the opening of a can, including; (1) the position of the can prior to its being pierced by the cutter element; (2) the position of the can as its end is being pierced by the cutter element; and (3) the position of the can as the end is being sheared therefrom are uniform. When the can feed wheel rotates in the counter-clockwise direction, it is important that the can be positioned in such a manner that its axis is slightly counter-clockwise from the vertical (the same direction as the feed wheel rotates) as the end of the can is being pierced by the cutting element and also while the end is being sheared from the can. Such slight counter-clockwise positioning of the can during these phases of operation of the opening of the can vastly contribute to maintaining the rim or flange of the can on the periphery of the can feed wheel. If the movable can guide is on such side of the can feed wheel, the can would be tilted the opposite direction (at least while the end is being pierced by the cutting element) and the rim or flange of the can would be prone to run off of the periphery of the can feed wheel. It should be pointed out that if the can feed wheel is to be rotated clockwise, the fixed can guide should be on the opposite side of the can feed wheel.

These and other objects of the invention, together with the features of novelty appurtenant thereto, will appear in the course of the following description.

DETAILED DESCRIPTION OF THE INVENTION

In the accompanying drawings, which form a part of

the specification and is to be read in conjunction therewith and in which like reference numerals are employed to indicate like parts of the various views:

FIG. 1 is a front elevational view of a power operating can opener showing the operating parts in a normal or at rest position;

FIG. 2 is a front elevational view of the upper portion of the can opener shown in FIG. 1 but with the cutter mounting plate removed and with the outer end of the can piercing lever shown broken away;

FIG. 3 is a rear elevational view of the cutter mounting plate;

FIG. 4 is a rear elevational view of the can opener frame and operating parts normally associated therethrough but with a portion of the conventional gear train broken away to disclose some of the components and the broken line indicative of alternative positions of the various parts;

FIG. 5 is a rear elevational view of the upper portion of the can opener frame shown in FIG. 4 but with the latch structure removed to more clearly show the construction of the movable can guide supporting member and with the broken lines indicating the hand lever and cutter mounting plate and associated elements being moved to the uppermost position;

FIG. 6 is a side elevational view of the frame and corresponding operating parts of the can opener taken from the right hand portion of FIG. 1;

FIG. 7 is a view similar to FIG. 6, however taken from the left side of the can opener shown in FIG. 1;

FIG. 8 is a front elevational view of the upper portion of the can opener shown in FIG. 1 with the broken line indicating the position of the hand lever and cutter mounting plate when same are moved to the uppermost position.

Turning now more particularly to the drawings, reference numeral 1 generally designates the upright frame of the can opener which will include the suitable apertures in order to accommodate the can feed wheel drive shaft 3 with the serrated can feed wheel 2 located thereon. As shown in FIG. 6, the drive shaft 3 is journaled in a fixed boss 4 (same being integrally formed on the rear surface of frame 1) and is rotated through suitable reduction gearing by a conventional electric motor M, preferably of the economical shaded pole type.

As shown in FIG. 2, frame 1 is provided with three small forwardly extending bosses 5 which provide a plane surface so that the pivoted end of a later described cutter mounting plate 6 may seat there against. A conventional can guard 7 will be fixedly attached to frame 1 at the usual location below the can feed wheel 2. Finally, frame 1 is provided with hole 8 through which the tapered end of a stud 9 may extend for the purpose of removably attaching the cutter mounting plate 6 to the frame in an operative position.

As will be seen, stud 9 is anchored in cutter mounting plate 6 and is a hardened part that is provided with an annular groove 10 (not shown) which receives a portion of the retaining latch 11 to maintain the cutter mounting plate 6 firmly seated against the forward vertical surfaces of the bosses 5 when assembled on the can opener frame.

A cutter wheel 12 is designed to be journaled on a stud that is anchored in boss 12a on the cutter mounting plate 6 and is designed to have limited wobble

movement similar to that shown in U. S. Pat. No. 3,314,144.

A can piercing lever 13 is permanently pivoted to frame 1 by the shoulder rivet 14. The forward end portion of rivet 14 extends through a suitable hold in can piercing lever 13 and is swaged over (preferably by hot-heading process) to securely anchor the rivet (14) in can piercing lever 13. The intermediate diameter portion 15 (not shown) of rivet 14 extends through a substantially horizontal slot 16 with the length of this portion 15 being slightly greater than the thickness of frame 1 in the area through which it extends. While slot 16 is shown as substantially horizontal, it may be counteracted in any other desirable manner. It is preferable to select the length of horizontal slot or opening 16 so that the above mentioned intermediate portion 15 (not shown) of the shoulder rivet 14 can not engage either end portion thereof under any condition of operation. However, if other limiting means is not employed for that purpose, the slot 16 can be terminated at its left end (when viewed from the front of the can opener as in FIG. 2) to limit the counter-clockwise swinging of can piercing lever 13 and the cutter mounting plate 6. Also, the height of the horizontal slot 16 is selected to be greater than the diameter of the intermediate portion 15 (not shown) of the rivet 14 in order to permit the cutter mounting plate 6 to rotate counter-clockwise (as viewed from the front) from its normal horizontal position approximately 4°.

30 The can piercing lever 13 and the cutter mounting plate 6 are connected by the inserting of shoulder stud 18 (which is anchored in cutter mounting plate 6 by hot-heading process) into a suitable hole 19 (see FIG. 2) of the lever 13. As will be seen, the upward swinging of can piercing lever 13 will accordingly result in the counter-clockwise rotation of cutter mounting plate 6 and this movement will be due, in part, to the above described interconnection. Also, a tension spring 13a will be hooked over the grooved rearmost extension 14a of rivet 14 (see FIGS. 4 and 5) and over rearwardly extending boss 13b of frame 1. Accordingly, the lever 13 is biased to the solid line position in FIGS. 4 and 5, thereby facilitating the alignment and re-installation of the cutter mounting plate 6 on the remainder of the can opener (e.g., stud 18 will always be aligned with hole 19 when parts are in the rest position).

50 A switch control lever 21 is pivoted to the rear side of frame 1 by the shoulder rivet 20 which is anchored in frame 1. Lever 21 is free to swing about the rivet 20 within prescribed limits and is provided with a hole 22 (not shown) through which the intermediate diameter portion of rivet 20 extends, thereby accomplishing the above mentioned pivotal connection. When the can opener is in the rest condition, the free end (see FIG. 4) of lever 21 is urged downwardly to seat on the rearwardly extending boss 23 of frame 1 by a tension spring 23a, one end of same being hooked in hole 24 of lever 21 while the other end thereof is hooked over a suitable boss 24a (not shown) of frame 1 therebelow.

60 The switch control lever 21 is provided with a substantially horizontal opening 25 that overlies horizontal opening 16 of frame 1 but which is of a larger size as indicated in the various views. When the can opener is in the rest condition, the upper edge of slot 25 in lever 21 will not only be horizontal (FIG. 4) but the largest diameter portion of shoulder rivet 14 will seat upwardly against the upper edge of lever 21. The can piercing

lever 13 will be substantially horizontal, with the upper edge of notch 26 of can piercing lever 13 seating downwardly (and providing a fulcrum for the can piercing lever) on the cooperating boss 27 which extends forwardly from frame 1. In this condition, there will be a few thousandths of an inch clearance between the circumference of the intermediate portion 15 (not shown) of the shoulder rivet 14 and the lower edge of slot 16 of frame 1. When sufficient downward force is applied to the free end of can piercing lever 13, the free end of lever 13 swings downwardly (fulcrums on boss 27), against the tension of spring 23a, until the circumference of the intermediate portion 15 (not shown) of rivet 14 seats upwardly against the upper edge of slot 16 of frame 1. In this condition, the axis of the shoulder rivet 14 will substantially be in the lateral plane of the axis of shoulder stud 18. The lower edge of opening 25 (of lever 21), as well as the ends of the opening, are never engaged by the largest diameter portion of the shoulder rivet 14 that extends through said opening.

As shown in FIGS. 4, 5 and 6, a portion of the free end of switch control lever 21 is offset rearwardly from frame 1 and has a hole 28 located therein in which the upper end of a switch actuating rod 29 is pivoted. The lower end of the switch actuating rod 29 is suitably supported for free vertical movement and extends through a hole (not shown) in bracket 31 which extends rearwardly from frame 1. A conventional switch S, of the normally closed type, and having a plunger P, is mounted on frame 1 for engagement with the lower end of the actuating rod 29. The length of the switch actuating rod 29 is set so switch S will always be in the "off" condition when the free end of the lever 21 seats downwardly on stop boss 23 and will always be "on" when the intermediate diameter portion 15 of the shoulder rivet 14 seats upwardly against the upper edge of slot 16 of frame 1 (with suitable over-travel both directions).

The upper left portion (as seen from the front) of can piercing lever 13 immediately adjacent the shoulder rivet 14 is offset to provide the required seating surface against frame 1 to permit clearance between the major portion of lever 13 and any decorative part that might be affixed to frame 1 between such major portions of the lever and the frame. This offset portion is designated by the numeral 32 in FIG. 2. As is customary, lever 13 is also provided with the normally flat upper area 33 which allows the user to apply force thereon in order to swing the lever downwardly.

As suggested above, the latch 11 is operated by the depressing of the push button or knob 44 in a manner similar to that disclosed in U. S. Pat. Nos. 3,496,635 and 3,520,056. Further, this latch is urged upwardly at all times by the tension spring 44a so that it engages stud 9 of the cutter mounting plate 6 and draws the same snugly against the bosses 5 on the forward portion of frame 1.

A fixed can guide 62 is pressed in a suitable hole in frame 1 and extends substantially forwardly of the face of can feed wheel 2. Additionally, a movable can guide 63 is anchored in the lower end of a movable can guide supporting link 64 (preferably by hot-heading process) and extends forwardly of the face of can feed wheel 2 by approximately the same distance as fixed can guide 62. In order to facilitate the positioning of the movable can guide a substantially triangularly shaped opening 65 is provided in frame 1 so that the movable can guide

may extend therethrough into operating proximity with the can to be opened. Further, the cutter mounting plate 6 is provided with a substantially rectangularly shaped opening 66 that, when mounted on the frame, overlies the opening 65 of frame 1 so that movable can guide 63 is accommodated.

As shown in FIG. 5, the upper end of the movable can guide supporting link 64 is provided with an elliptical opening 67 with the long axis of the opening extending through the axis of movable can guide 63. The supporting link as suggested above is mounted on shoulder rivet 68 on the rearward side of frame 1 for limited pivotal and longitudinal movement. In this regard, the intermediate diameter portion (not shown) of the rivet 68 extends through the opening 67 of link 64. Accordingly this interconnecting portion of shoulder rivet 68 operates to permit free pivotal and longitudinal movement of link 64 but, at the same time, substantially maintains the link 64 in a plane paralleling that of the rearward surface of frame 1.

A rearwardly bent portion 69 of link 64 is provided with a suitable hole (not shown) so that a tension spring 72 may have an upper end portion hooked therein while the other end is hooked over a suitable boss 72a which also extends rearwardly from frame 1. It should be noted that the spring 72 is positioned in such an angle that its force will not only urge the movable can guide 63 downwardly at all times but will also urge can guide toward the left (as viewed from the front of the can opener) at all times. With the can opener at rest, a clearance notch 73 is provided in cutter mounting plate 6 so that the fixed can guide may locate therein and not interfere with the working positions of the cutter mounting plate.

Finally, the operation discussed, infra, may be facilitated by identifying the left side of the triangular opening 65 of frame 1 (see FIG. 2) by the numeral 76, the upper side by the numeral 74 and the inclined third side bears the designation 75. Also, for identification, the left side of rectangular opening 66 (when viewed from the front as in FIG. 1) in cutter mounting plate 6 is designated by the numeral 77, and the right side of the same opening is designated by numeral 78.

OPERATION

The latch 11, preferably through the wedging action of the sum surfaces 11b against rearward boss 11a, will draw the stud 9 of mounting plate 6 rearwardly so that the cutter mounting plate seats on bosses 5 and on the forwardly extending left hand portion of can piercing lever 13. This arrangement assures proper alignment between the can feed wheel and the cutting element as suggested in the McLean et al. U.S. Pat. No. 3,496,635. The operating thrust, whenever a can is engaged in the can opener, is such that slight clearance can be expected to exist between the right end of cutter mounting plate 6 and the adjacent surface of the can piercing lever 13, thereby eliminating friction that could impede rotation of one of these parts relative to the other during the automatic shut-off phase of operation of the can opener.

As suggested above, the cutter mounting plate 6 swings on the axis of hole 8 of frame 1 but remains on the outer surface of the three bosses 5 whenever swung to any possible operating position. Accordingly, when all parts of the can opener are in the rest condition, the can piercing lever 13 will be substantially horizontal,

with the upper edge of notch 26 of the lever seating downwardly on boss 27 of frame 1. In this position, the circumference of the largest diameter portion of shoulder rivet 14 seats upwardly against the upper edge of opening 25 of switch control lever 21. There will be a few thousandths of an inch clearance between the circumference of the intermediate diameter portion 15 (not shown) of shoulder rivet 14 and the lower edge of slot 16 of frame 1. Also, with all parts of the can opener in the rest condition, the movable can guide supporting link 64 is pivoted to frame 1 by the shoulder rivet 68, the intermediate diameter portion of the link connecting rivet 68 is in the upper end of the elliptical slot 67 of link 64.

In any possible operating condition, there is always clearance between movable can guide 63 and the inclined edge of side 75 of opening 65 in frame 1. When all parts of the can opener are in rest condition, the movable can guide 63 will not only be urged to its extreme downward position, but will also be urged to its left-most position, seating against the edge or side 76 of the opening 65 in frame 1. As shown in FIGS. 1 and 8, whenever the movable can guide 63 is in engagement with the edge or side 76 of the opening 65 in frame 1 there will always be some clearance between the guide and the right side 78 of rectangular opening 66 of cutter mounting plate 6. Cutter mounting plate 6 can be swung approximately 6° counter-clockwise (as seen from the front) before the left side 77 of the rectangular opening 66 thereof will engage the movable can guide 63. The movable can guide 63 can never engage the upper or lower ends of the rectangular opening 66 of cutter mounting plate 6. Further, it is preferred that the movable can guide 63 never engage the upper side 74 of the triangular opening 65 in frame 1.

When all parts are in the rest condition as shown in FIGS. 1 and 4, it will be obvious that cutter mounting plate 6 can readily be removed by drawing same forwardly without interference with either can guide (after first pressing the latch knob or push button 44 to its extreme downward position).

To re-install cutter mounting plate 6 on the remainder of the can opener, it is only necessary to depress the latch knob or push button 44 and to hold plate 6 in an approximate horizontal position. The tapered end of stud 9 is then inserted in hole 8 of frame 1 and the plate is moved rearwardly until it seats on the 3 bosses 5 and on the forward portion of piercing lever 13, as the latch knob or push button 44 is permitted to rise under the impetus of the latch tension spring 44a. Since a substantial length of stud 9 will have entered the hole 8 of frame 1 before cutter mounting plate 6 arrives in a contacting relationship with the plane of the forward ends of can guides 62 and 63, the plate 6 automatically clears the can guides as it moves rearwardly (assuming the plate is held in an approximately horizontal position). Also, in as much as movable can guide 63 will extend forwardly through the opening 66 of plate 6 before the pivot stud 18 arrives in the plane of can piercing lever 13, only limited free oscillation of the plate 6 on its pivot 8 is possible. By such limited oscillation, the user can readily engage the tapered end stud 18 in the hole 19 of the can piercing lever 13. The engagement of the can piercing lever notch 26 with boss 27 maintains lever 13 in the position required to permit re-installation of the cutter mounting plate on the remainder of the can opener.

When can piercing lever 13 is swung upwardly or counter-clockwise (as viewed from the front) to its extreme position, cutter mounting plate 6 will be rotated approximately 34° from its normal horizontal position. After cutter mounting plate 6 swings counter-clockwise approximately 6° from its normal horizontal position, additional counter-clockwise swinging thereof causes the movable can guide 63 to move upwardly to the right through engagement of the left side 77 of opening 66 of cutter mounting plate 6 with the movable can guide 63. Accordingly, such displacement of movable can guide 63 is accomplished through approximately 28° rotation of cutter mounting plate 6, thereby requiring the application of much less force to lever 13 than is required when the movable can guide must be displaced by a much lesser rotational arc on the part of the cutter mounting plate.

After the user swings can piercing lever 13 counter-clockwise to its extreme position, movable can guide 63 will have been raised sufficiently to enable the insertion of the rim or flange of the can over the periphery of the can feed wheel 2 and under the can guides 62 and 63. The user then swings can piercing lever 13 downwardly to its extreme position, thereby resulting in the cutter wheel 12 first seating firmly on the end of the can. Additional swinging of the lever 13 causes the switch control lever 21 to rotate clockwise (as viewed from the rear of the can opener), against the tension of spring 23a. This results in a changing of switch S from the "off" condition to the "on" condition and the starting of motor M. Further downward swinging of lever 13 causes the intermediate diameter portion 15 (not shown) of the shoulder rivet 14 to seat upwardly against the upper edge of slot 16 of frame 1. The continued downward swinging of the can piercing lever 13 to its downwardmost position causes cutter wheel 12 to pierce the end of the can.

Resistance of the end of the can to shear by cutter wheel 12 causes the portion 15 (not shown) of shoulder rivet 14 to continue in engagement with the upper edge of slot 16 of frame 1. However, after the end has been completely sheared from the can, the force of spring 23a moves the free end of the switch control lever 21 downwardly until it seats on boss 23 of frame 1, thereby changing the switch from the "on" condition to the "off" condition and shutting off the motor M.

As the user commences the swinging of the can piercing lever 13 downwardly from its extreme upward position, the movable can guide 63, under impetus of its spring 72, moves downwardly and to the left until in firm engagement with the top of the rim or flange of the can. Movement toward its leftmost position (wherein movable can guide 63 engages the left side of opening 65 of frame 1) is positive by its engagement with the right side 78 of opening 66 of the cutter mounting plate 6. However, friction between movable can guide 63 and the top of the rim or flange of the engaged can, assisted by the selected direction of force by the spring 72, always moves can guide 63 to its desired position (in engagement with left side 76 of opening 65 of frame 1).

When a can is engaged in the can opener, movable can guide 63 will be substantially above its illustrated position in FIGS. 1 and 2 but will stay in engagement with the left side 76 of opening 65. It should be noted that the opening 66 of the cutter mounting plate 6 is free of the movable can guide 63 at all times while the

end is being sheared from the can (so as not to interfere with the automatic shut-off function) as well as after the automatic shut-off has occurred. Obviously, the user can remove the can from the can opener by swinging the can piercing lever 13 upwardly to its extreme position. The conventional can guard 7 maintains the side wall of the can engaged in the can opener at the desired angle relative to the face of feed wheel 2.

It will be noted that the spring-urged movable can guide 63, in cooperation with the fixed can guide 62, 10 forces the rim or flange of an engaged can downwardly on the toothed periphery of can feed wheel 2 as required to provide the necessary traction for the feeding of the can with respect to the cutter wheel 12.

The switch S can be changed from the normally "off" 15 condition to the "on" condition by depressing the free end of the can piercing lever 13. Accordingly, if the can opener is also provided with a knife sharpener (not shown), it is not necessary to provide any switch manipulating means for operating the conventional cutlery grinding means separate from the means provided for operating the can opener. This is specifically accomplished by fulcruming the can piercing lever 13 at a point on frame 1 intermediate the free end of the lever and the point at which it is pivoted to the cutter 20 mounting plate 6. Fulcruming of the can piercing lever at a point on the frame of the can opener for this purpose has been previously discussed in the McLean U.S. Pat. No. 3,277,570.

Spring 23a, which urges the free end of switch control lever 21 downwardly at all times, must have sufficient force to move the intermediate portion 15 (not shown) of shoulder stud 14 from its uppermost possible position in slot 16 of frame 1 (through which it extends) to near its lowermost possible position therein upon completion of the severing of the end from an engaged can, to thereby complete the automatic shut-off and stop the motor as described above. However, force of tension spring 23a must never be sufficient to so move stud 14 from its uppermost position in slot 16 to its lowermost position therein while the end of the engaged can is being sheared by the cutter wheel 12. The preferred strength of this tension spring would be approximately midway between the minimum strength required to so move stud 14 from its uppermost position to its lowermost position when the end has been completely sheared from the can and the maximum strength the spring could have without moving stud 14 from its uppermost to its lowermost position while the end is being sheared from the can.

From the foregoing, it will be seen that this invention is one well adapted to attain all the ends and objects herein set forth, together with other advantages which are obvious and which are inherent to the structure.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

I claim:

1. In a power operated can opener having an upright frame with a can feed wheel supported thereon, said

frame having a bearing opening therein, a hand lever and a releasable latch affixed to said frame, the combination therewith of

a cutter mounting plate having a cutter element mounted thereon, said plate having first and second pin members extending therefrom, said first pin member engaged within said bearing opening and releasably retained by said latch thereby removably mounting said plate on said frame, said cutter mounting plate being fixedly pivoted about said bearing opening, and,

means for swingably mounting said hand lever to said frame, said hand lever having an aperture therein, said second pin member removably and separably located without the use of tools within said lever aperture and operable to permit pivotal movement between said lever and said plate, said lever swinging movement thereby effecting pivoting of said cutter element and said cutter mounting plate on said first pin member toward and away from said feed wheel.

2. The combination as in claim 1 including an electric motor drivingly connected with said feed wheel, a switch means connected with said motor and having a motor energized condition and a motor de-energized condition, a second opening in said frame, said swingably mounting means including a pivot member located thereon and extending through said second opening, a motor control means mounted on said frame, said pivot member extending through said second opening and contacting said motor control means, said pivot member being operable to move said motor control means in a direction to effect said motor energized condition and the driving of said can feed wheel when said lever effects the swinging of said cutter mounting plate and said cutter element into a can piercing position with a can having an end to be sheared by said cutter element, and

means for releasably connecting said first cutter mounting plate pin member to said frame, said connecting means including a latch member for retaining said cutter mounting plate on said frame for the can shearing operation of said can opener and for permitting axial separation of said pin member and said bearing opening when said latch member is moved in a preselected direction.

3. The combination as in claim 2 including means connected with said motor control means to automatically cause said motor control means to de-energize said motor when the cutting of the end of the can has been completed.

4. The combination as in claim 1 wherein said frame has a fixed can guide extending therefrom, a second can guide, means for movably mounting said second can guide with respect to said frame, an aperture in said cutter mounting plate, said second can guide extending through said aperture in said cutter mounting plate, said cutter mounting plate having a portion thereof operable to engage said movable can guide and to move same away from said can feed wheel to permit the insertion of a can or the removal of a can from said can opener in accordance with the movement of said hand lever.

5. The combination as in claim 4 wherein said can feed wheel rotates in a pre-selected direction, said fixed can guide located on said frame and spaced away from

said can feed wheel in a direction that is opposite to the direction of rotation of said feed wheel.

6. The combination as in claim 1 wherein said swingably mounting means for said hand lever includes said frame having elongated opening therein, a fixed pivot member extending from said lever and extending through said elongated opening, said lever being operable to swing about the axis of said fixed pivot member and to move substantially through the length of said elongated slot in said frame as said lever effects the pivoting of the said cutter mounting plate toward and away from said can feed wheel.

7. The combination as in claim 6 including a resilient

member connected between said frame and said fixed pivot member, said resilient member operable to urge said fixed pivot member in a preselected direction within said elongated opening.

5 8. The combination as in claim 2 wherein said frame includes a boss member extending from said frame, said lever being swingable in a preselected direction to contact said boss and to move in a direction to effect the movement of said pivot member to operate said switch means and energize said motor with a can being engaged in said can opener.

UNITED STATES PATENT OFFICE
CERTIFICATE OF CORRECTION

Patent No. 3,787,967

Dated January 29, 1974

Inventor(s) Robert E. McLean

It is certified that error appears in the above-identified patent and that said Letters Patent are hereby corrected as shown below:

Column 1

Line 42 - Word "level" should be --lever--.

Column 2

Line 19 - Word "of" should be --on--.

Column 3

Line 1 - Word "is" should be --are--.

Column 4

Line 5 - Word "hold" should be --hole--.

Column 6

Line 47 - Word "sum" should be --cam--.

Column 12

Next to last line - Word "with" should be --without--.

Signed and sealed this 18th day of June 1974.

(SEAL)
